UNITED STATES PATENT OFFICE.

HARRY DIXSON, OF PELLA, IOWA, ASSIGNOR TO ROLSCREEN COMPANY, OF PELLA, IOWA.

RETHREADER FOR SCREENS.

Application filed February 19, 1927. Serial No. 169,556.

The object of my invention is to provide a rethreader whereby the side edges of a screen may be rethreaded into a guide track after it has accidentally been removed therefrom.

More particularly it is my object to provide a casing adapted to receive a rolling window screen in rolled up position adjacent the upper end of a track and in position adjacent the side edge of the screen itself having a notch therein whereby the screen may pass around or over the upper end of the track through said notch into the casing so that when the screen is again withdrawn or pulled from the casing, it will have its side edge in position to travel in the guide track.

With these and other objects in view, my invention consists in the construction, arrangement and combination of the various parts of my rethreader for screens, whereby the objects contemplated are attained, as hereinafter more fully set forth, pointed out in my claims, and illustrated in the accompanying drawings, in which:

Figure 1 is a perspective view of a portion of a casing with the upper end of a track illustrating the notch formed in the casing above the track.

Figure 2 is a sectional view taken on the line 2-2 of Figure 1, illustrating the manner of the screen passing around and over the upper end of the track and through the notch in the casing.

Figure 3 is a sectional view taken on the line 3-3 of Figure 1 and

Figure 4 is a sectional view taken on the line 4-4 of Figure 1.

In the embodiment of my invention as illustrated in the accompanying drawings, I have used the reference character A to indicate generally a four sided casing adapted to house a rolling window screen. The casing A adjacent one side and its bottom is formed with a slot opening 10 through which the screen 12 passes.

The screen 10 is not illustrated in Figure 1 of the drawings. The casing A is formed with partition walls or bearing plates 14 spaced inwardly from the ends of the casing. A guide track B is formed with a flat fastening flange 16 which projects up into the casing A adjacent the bearing plate 14 as at 18.

The track B also includes a tubular shaped guide portion 20 having a slot or slit opening 22 therein. The guide portion 20 is positioned adjacent the bearing plate 14 as

clearly illustrated in Figure 2 of the drawings.

The upper end of the guide 20 is in alignment with the slot opening 10 in the casing A so that when the screen 12 is withdrawn through the opening 10, then the side edge of the screen 12 may pass into the guide portion 20 and within the slit opening 22.

The side edges of the screen 12 are formed with a plurality of thickened up portions or clips 24. The clips 24 are of greater thickness than the width of the slit openings 22 so that when the clips 24 are received within the guide portion 20 of the track B, they will remain therein unless undue pressure is applied upon the screen and in that case the guide portion 20 will expand or have its sides spread apart for allowing the clips 24 to pass through the slit opening 22.

It will be noted that the tubular portion is made of metal and there exists a certain amount of resiliency therein so that the edges of the screen together with the clips thereon may be pulled through the slit openings 22.

When the screen has been pulled from the guide portion 20 of the track B it is desirable to get it rethreaded or to again have it re-enter the guide portion 20 and in order to take care of this, I provide a notch 26 in the front wall of the casing A just above the guide portion 20 of the track B.

It will be understood that the screen 12 travels in two guide tracks B, one adjacent each edge of the screen 12. The casing A is, of course, formed with a notch 26 above each of the tracks B. The notch 26 is slightly greater in width than the guide portions 20 so that the edge of the track B adjacent the slit opening 22 is spaced a slight distance from one of the walls of the notch 26 as clearly illustrated in Figure 2 of the drawings.

This space serves to allow the screen 12 to pass around the track B. When the screen 12 is forced from the guide portion 20 of the track B, it is necessary to have the clips 24 pass back into the guide portion 20 and this may be accomplished by simply forcing the screen upwardly or moving it to its rolled up position at which time the punched out or pushed out portion will pass over the upper edge of the guide portion 20 into the casing A through the notch 26.

When the screen is again withdrawn, the side edge thereof, will register with the guide 20 and pass therein thus causing the side edge

of the screen together with the clips 24 thereon, to be rethreaded in the guide portion 20 of the track B.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. In combination with a screen having thickened portions on its side edge, a guide track provided with a slit opening extending lengthwise of the track, the side edge and thickened portions of the screen being received in the guide track, said thickened portions being of greater size than the normal width of said slit opening whereby the thickened portions will normally remain in said track and a casing having an opening therein and having a notch formed therein, said notch being positioned at the upper end of said track whereby if the side edge and thickened portion of the screen are accidentally withdrawn from the guide track, they may travel into

said casing over the upper end of said track and through said notch for allowing them to again reenter said track when the screen is withdrawn.

2. In combination with a guide track having a tubular portion provided with a slot to receive the side edge of a screen a casing having an opening in line with the slot in said track, said casing being positioned just above the track, said opening in the casing being in the bottom thereof and near one side, the side of the casing being cut away for a slight distance above the bottom and above the tracks.

3. In combination with a screen, a guide track provided with a slit opening extending lengthwise of the track, the side edge of the screen being received in the guide track, and a casing having an opening therein and having a notch formed therein, said notch being positioned at the upper end of said track whereby if the side edge of the screen is accidentally withdrawn from the guide track, it may travel into said casing over the upper end of said track and through said notch for allowing it to reenter said track when the screen is withdrawn.

HARRY DIXSON.
